TRAFFIC CONTROL SYSTEM

Phillips Thomas, Edgewood, Pa., assignor to
Westinghouse Electric & Manufacturing Com-
pany, a corporation of Pennsylvania

Application February 14, 1931. Serial No. 515,714

1 Claim. (Cl. 177—339)

My invention relates to traffic-control systems and has particular relation to traffic-control systems of a type utilized at major highway intersections.

5 Under ordinary circumstances, traffic-control systems are provided with a specific design directed to the characteristics of the highway intersection at which they are intended to be utilized. The system constructed according to my 10 invention is particularly adapted to be utilized at an intersection where the traffic along one lane is comparatively heavy and the traffic along the intersecting lane is comparatively light, at certain periods of the day. At other periods of the 15 day, the traffic along the latter lane is comparatively heavy and the traffic along the former lane is comparatively light. During the remaining periods, the traffic along both lanes is substantially of equal density.

20 It is, accordingly, an object of my invention to provide a traffic-control system particularly adapted to be utilized at a highway intersection at which the traffic along one lane is heavy, as compared with the traffic along an auxiliary 25 lane at certain periods, while the converse is true at certain other periods.

Another object of my invention is to provide a traffic-control system particularly adapted to be utilized at an intersection wherein the ratio of 30 the density of traffic in one direction to the density of traffic in the remaining direction varies from a comparatively large improper fraction to a comparatively small proper fraction.

A more specific object of my invention is to 35 provide apparatus of a type responsive to the condition of the traffic along a plurality of intersecting lanes; said apparatus being adapted to regulate the condition of a traffic-signalling device that normally operates a "stop" signal for all 40 of the lanes of the intersection.

Another specific object of my invention is to provide vehicle-actuated traffic-control apparatus adapted to be utilized at the intersection of a plurality of lanes; the apparatus being of such 45 structure that a traffic-signalling device shall be controlled by a vehicle moving along one lane, to indicate a "go" signal for that particular lane and to indicate a "stop" signal for the intersecting lanes which signals shall continue to be dis- 50 played for a period of time predetermined by the period required by the vehicle in passing through the intersection.

More concisely stated, it is an object of my invention to provide for an intersection vehicle- 55 operated traffic-control apparatus, of a type hav-

ing a plurality of possible conditions of operation; the particular conditions of operation to be utilized at a given time being dependent on the condition of the traffic along the lanes forming the intersection at the particular time. 60

According to my invention, I provide a traffic-control system comprising a plurality of street devices, located along the lanes of a particular intersection and adapted to be controlled by vehicles moving along the lanes. The street devices are associated with a system of relays, with a program controller and with a signalling device. 65

Under normal circumstances, the signalling device displays a "stop" signal for all lanes passing through the intersection. A vehicle 70 moving along one intersection causes actuation of the street device which, in turn, responds by coacting with a system of relays and causing a "go" signal to be displayed along the particular highway along which the vehicle is moving and a "stop" signal to be displayed along the intersecting highway or highways. The particular system of signals thus controlled by the vehicle persists until a vehicle moving along an intersecting highway causes it to be changed to 75 a system wherein the "go" signal is indicated for the particular lane along which the latter vehicle is moving and the stop signal is indicated for the remaining lanes. 80

However, if two vehicles should appear at the 85 intersection, each along a separate lane, within a predetermined period of time, the signalling system is not immediately changed, but the traffic-signalling device is connected to the program controller. At the instant that the connection is made, a "caution" signal is displayed for a short time, after which the "go" signal is displayed for a predetermined period of time along the lane along which the first vehicle appeared. At the termination of this period the 95 "go" signal is transferred to the intersecting lane along which the second vehicle appeared. I accomplish this object by regulating the direction of rotation of the program controller in accordance with the initial condition of the lanes 100 at the intersection.

To give a concrete example, I shall assume that the system is disposed at an intersection of two lanes A and B. When there is no traffic along the lanes, a "stop" signal is displayed 105 for both lanes. If a vehicle now appears along the lane A, the system of relays is energized and, in turn, actuates the signalling device to cause a "go" signal to be displayed for the lane A and a "stop" signal to be displayed for the 110

lane B. The signal persists for a predetermined time of sufficient length to give the vehicle that actuated the street device sufficient time to pass through the intersection.

5 If, during this period of time, a vehicle appears along the lane B, the program-control motor is actuated, and a "caution" signal is displayed. Moreover, by the initial condition of the lane A, the interconnection of the starting windings 10 and the main windings of the program-control motor is so adjusted that its direction of rotation is predetermined in such manner that, after the caution period, the signals continue to indicate "go" for the A highway and "stop" for 15 the B highway for the period of time necessary for the original vehicle to pass through the intersection.

It will be furthermore noted that the position in which the disk of the program-control motor 20 stops can only be predetermined within 180°. That is to say, the program-control motor stops in a position determined by the last highway along which a vehicle appeared when it was in 25 inactive condition. I have, consequently, incorporated a reversing relay in the system that is so interconnected with the relays determining the direction of rotation of the motor in accordance with the initial condition of the highways as to cause the motor to rotate in the 30 proper direction to actuate the signals in their proper succession.

The specific embodiment of my invention described herein incorporates a plurality of pairs of control devices, (in this case, of the photo-sensitive type), each pair being associated with a 35 particular lane and being adapted to actuate a relay. Each relay is, in turn, adapted to excite the coil of a time-delay relay which is energized instantly but reverts to its deenergized condition 40 after a predetermined time.

When only one time-delay relay is energized, it causes its corresponding relays in two pairs of interlocked relays to be energized. One pair of interlocked relays are associated with four 45 relays that independently regulate the condition of the signals at the intersection, each relay of the interlocked pair being adapted to regulate the activity of two relays associated with the signals of a particular lane.

50 The interlocked relays of the remaining pair are adapted to regulate the direction of rotation of a program-control motor, through the contactors of a reversing relay. The state of excitation of the relay is predetermined by the orientation of the program-control disk in its latest 55 resting position.

When both time-delay relays are energized, the coil of a third time-delay relay becomes excited and, in turn, causes a plurality of latch 60 relays to be energized.

One of the latch relays opens the normal circuits through the coils of the four relays associated with the signals, certain of which were energized by one pair of interlocked relays, and closes 65 the circuit through the windings of the program controller. The remaining latch relay completes circuits through the contacting segment of the program-control disc and through the coils of certain of the four relays associated with the 70 traffic signals.

75 When the program-control motor is again de-energized, the tripping devices of the lock relays are released by the closing of a circuit through contactors of the four relays associated with the traffic signals.

The novel features that I consider characteristic of my invention are set forth with particularity in the appended claim. The invention itself, however, both as to its organization and its method of operation, together with additional objects and advantages thereof will best be understood from the following description of a specific embodiment, when read in connection with the accompanying drawings, in which

80 Figure 1 is a schematic view showing a vertical section of a lane that traverses a highway intersection at which an embodiment of my invention is disposed, and

85 Figs. 2 and 3, jointly constitute a diagrammatic view showing the principal elements of a control system constructed according to my invention.

90 The apparatus shown in the drawings comprises a signalling device 1, including a plurality of signals 3, 5, 7, 9, and 11 adapted to be displayed at the intersection 12 of the highways 13 and 15, containers 17, 19, 21 and 23 having disposed therein photo-sensitive devices 25, 27, 29 and 31 and containers 33, 35, 37 and 39 having sources of light 41, 43, 45 and 47 disposed therein that are adapted to excite the photo-sensitive 95 devices 25, 27, 29 and 31. When the light beam between one source, such as 41, and one associated photo-sensitive device 25 is interrupted by a vehicle 49, as shown in the drawings, the system of signals 1 is actuated to produce the necessary 100 signal displays for the particular highway 13 with which the tube 25 and the source 41 are associated.

105 In Figs. 2 and 3, the intersection 12 is shown in detail. The signalling device 1 is illustrated at 110 the center of the intersection and, for purposes of clarity, has been shown in detail.

Under normal circumstances, the photo-sensitive devices 25, 27, 29 and 31 disposed along the lanes 13 and 15 are in an excited state, and, in 115 consequence thereof, the exciting coils 51 and 53 of a plurality of relays 55 and 57 associated with the devices are in an energized condition.

120 As is shown in the drawings, a single relay coil 51 or 53 is connected in series with the photo-sensitive devices 25 and 31, or 27 and 29 disposed along a single highway 13 or 15 on both sides of the intersection 12. The relay coil 51 or 53, connected in series with the tubes 25 and 31, or 27 and 29, is, therefore, deenergized by the interruption 125 of the light passing through a single tube.

130 It is well to point out that it is necessary that the system be actuated by a vehicle appearing along either section of a lane 13 or 15. Advantage is therefore taken of the fact that the interruption of the light passing through one photo-tube of a group connected in series relationship is sufficient to open the series circuit. It is to be noted, however, that this particular feature 135 of my invention, relating only to the street device, is not to be regarded as a limitation thereof. It is equally as well possible to utilize a plurality of relays and to connect each relay with a particular photo-tube, or to connect the pairs of photo- 140 tubes in parallel with single relays.

145 Finally, it should be noted that I have illustrated a system wherein the photo-sensitive devices 25, 27, 29 and 31 are connected directly through the coils 51 and 53 of the mechanical relays 55 and 57. Under ordinary circumstances, these devices are adapted to actuate an electrical relay, (that is to say, a grid-controlled electric-discharge tube, for example) and the current from the tube is adapted to energize a mechan- 150

ical relay. The specific form of the mechanical relays that is shown is, therefore, only to be regarded as symbolical, and it is to be borne in mind that relays that are ordinarily used in the present connection are of the electronic type.

As shown in Figs. 2 and 3, the system is in its normal condition, that is, the "stop" signals 3 and 7 are indicated for both of the highways 13 and 15.

The "stop" signal 7 along one highway 15 is energized from the following circuit: from one bus 59 of an alternating-current supply line, through conductors 61 and 63, the movable contactor 65 of a relay 67, associated with the signalling system 1, conductor 81, the signals 7, connected in parallel relationship and conductor 71, to the remaining bus 73 of the alternating-current supply source. The "stop" signal 3 along the remaining highway 13 is energized from a circuit extending from one bus line 59 of the alternating-current supply source, through conductors 61 and 75, the movable contactor 77 of a second relay 79, conductor 69, the signalling lamps 3, connected in parallel relationship, and conductor 71, to the remaining terminal 73 of the alternating-current supply source.

When a vehicle now appears along one lane (say lane 13) the exciting coil 51 of the relay 55 associated with the photo-sensitive device 25 situated in the lane is deenergized, and a circuit is closed from one bus 83 of a direction current line, through conductor 85, the movable contactor 87 of the relay 55, that has been deenergized, conductor 89, the exciting coil 91 of a time-delay relay 93, and conductor 95, to the remaining direct-current bus line 97.

The time-delay relay 93 is of such structure that it closes instantly upon the excitation of its coil 91 but opens slowly when its coil is de-energized. The relay 93, therefore, remains in a closed condition for a predetermined period after the vehicle has left the intersection, and the relay 55 associated with the photo-sensitive device 25 has been deenergized.

The time-delay relay 93 is equipped with a plurality of contactors 99, 101 and 103. When it is energized, a circuit is closed from one direct-current bus line 83, through conductors 105 and 107, its upper movable contactor 99, conductor 109, the lower contactor 111 of one relay 113 of a pair of relays 113 and 115 comprising an interlocking system 117, conductor 119, the exciting coil 121 of the remaining relay 115 of the interlocked pair 117 and conductor 123, to the remaining direct-current bus line 97. At the same time, a second circuit is closed, from one direct-current bus line 83, through conductors 105 and 125, the contactor 101 of the time-delay relay 93, conductor 127, a contactor 129 of one relay 131 of a second pair 132 of interlocked relays 131 and 133, conductor 135, the coil 137 of the remaining relay 133 of the second interlocked pair and conductor 139, to the remaining direct-current bus line 97.

It will be noted that the lane 15 at right angles to the lane 13 (heretofore considered), is equipped with a similar system of relays including the relay 57 adapted to be deenergized from the photo-sensitive device 27 or 29 situated along the lane 15, and a time-delay relay 141 adapted to be energized through the contactor 143 of the relay 57 associated with the photo-sensitive devices.

The time-delay relay 141 is similar to the time-

delay relay 93 which was discussed hereinabove, and is equipped with a plurality of corresponding contactors 145, 147 and 149 that are adapted to close corresponding circuits through the two pairs of interlocked relays 117 and 132. In this case, a circuit is closed through the contactors 151 and 153 of relays 115 and 133 of pairs 117 and 132 of interlocked relays, the exciting coils 121 and 137 of which were energized in the above considered case, and through the coils 155 and 157 of the relays 113 and 131 of the pairs, and through the lower contactors 111 and 129, of which the energizing currents in the above hypothetical case passed.

It is to be noted that the activity of the individual relays 113, 115 and 131 and 133 in the pairs 117 and 132 are predetermined by the succession in which the street devices (say 25 and 29) are affected by vehicles. Thus, if the vehicle first appears along one lane 13, the relays 115 and 133 of the pairs are energized, and the remaining relays 113 and 131 of the pairs are prevented from becoming energized, while, if the vehicle appears first at the intersecting lane 15, the converse of the condition is produced. As will be seen hereinafter, the interlocked relays 117 and 132 are utilized, respectively, in determining the condition of the lights and in determining the direction of rotation of the motor.

The time-delay relays 93 and 141 are equipped with contactors 103 and 147 through which two parallel circuits are closed. One circuit extends from a direct-current bus line 83, through conductors 105 and 159, the contactor 103 of one relay 93, conductor 161, the exciting coil 163 of a third time-delay relay 165, and conductor 167, to the remaining direct-current bus line 97, and the remaining circuit extends from one direct-current bus line 83, through conductors 105 and 159, the contactor 149 of the remaining relay 141, conductors 169 and 161, the exciting coil 163 of the third time-delay relay 165 and conductor 167, to the remaining bus line 97 of the direct-current source.

The time-delay relay 165 is of a type adapted to close instantly when its coil 163 is deenergized and requiring a predetermined time for opening when its coil becomes energized. It will be noted that the relay 165 can only be deenergized when both of the relays 93 and 141, associated with the independent lanes 13 and 15, are energized, and, consequently, when two vehicles appear, one in each lane, within a predetermined time of each other.

Returning now to the case that was originally considered, (that is, to the case wherein a single vehicle appears along one lane 13, causing one time-delay relay 93 to become energized) it is seen that the excitation of the relay 115 of one pair 117 of interlocking relays causes a circuit to be closed from one direct-current bus line 83, through conductors 171 and 173, a movable contactor 175 of a latch relay 177, the exciting coil 179 of which is adapted to be energized through the contactors 181 of the time-delay relay 165, conductors 183 and 185, a movable contactor 187 of the energized relay 115 of one pair 117 of interlocked relays, conductor 189, the exciting coil 191 of a relay 193, associated with the street signals 1 and conductor 195, to the remaining direct-current bus line 97. A second circuit is opened from one direct-current bus line 83, through conductors 171 and 173, the movable contactor 175 of the relay 177, conductor 183, a sec-

ond movable contactor 197 of the relay 115 of the interlocked pair 117, that was disengaged from its corresponding fixed contacts 199 when the relay 115 was energized, conductor 201, the exciting coil 203, of the relay 79 associated with the signal lamps 1 and conductor 195, to the remaining bus line 97 of the direct-current source.

When the latter relay 79 is deenergized, the circuit, through the lamps 3 that indicate "stop" 10 along the highway 13, along which the vehicle appears, is broken. On the other hand, by reason of the fact that the relay 193 was simultaneously energized, a circuit is closed from one alternating-current bus line 59, through conductor 61, a movable contactor 205 of the relay 193, conductor or 15 207, the "go" signalling lamps 5, connected in parallel relationship and conductor 71, to the remaining terminal 73 of the alternating-current bus line.

20 It will be noted that, by the interruption of the beam exciting the photo-sensitive device 25 disposed along the highway 13, the signalling system 1 has been so actuated that a "go" signal 5 is indicated for the particular highway 13 for 25 which the beam was energized, while the "stop" signal 7 for the remaining highway 15 remains unaffected.

It is well to point out that an analogous system of relays is provided for opening the circuit 30 through the "stop" lights 7 that are displayed along the highway 15 and for closing the circuit for the "go" lights 9 along that highway when a vehicle appears along the highway 15 instead of along the former highway 13. The circuits associated with these relays are similar to the 35 circuits associated with the relays discussed hereinabove and, therefore, will not be traced in detail.

Heretofore, the only condition considered has 40 been that wherein a single vehicle moving along one of the intersecting lanes 13 actuated the control system associated with that lane and, consequently, produces a condition wherein the "go" signal is displayed for the highway along 45 which it is moving, and the "stop" signal is displayed for the remaining highway. If a second vehicle should appear along the remaining highway 15 during the interval in which the "go" signal is being displayed along the first highway, 50 the relay 57, associated with the photo-sensitive device 27 or 29 disposed on the highway, is de-energized, and a condition is obtained wherein both time-delay relays 93 and 141 are energized. The circuit through the coil 163 of the third time-delay relay 165 is then opened, and the 55 movable contactor 181, associated with the relay, immediately engages a plurality of corresponding fixed contacts 209.

When this condition is attained, the interlocked pairs of relays 117 and 132 remain unchanged in their activity, while the coils 179 and 211 of two latch relays 177 and 213 are energized through the contactor 181 of the time-delay relay 165.

65 The circuit through the coil 211 of one relay 213 extends from one direct-current bus line 83, through conductors 215 and 217, the movable contactor 181 of the time-delay relay 165, conductor 219, the exciting coil 211 of one relay 213 70 and conductor 221, to the remaining bus line 97 of the direct-current source. The circuit of the remaining relay extends from a direct-current bus line 83, through conductors 215 and 217, the movable contactor 181 of the time-delay relay 165, conductor 219, the exciting coil 179 of

the relay 177 and conductor 223, to the remaining bus line 97 of the direct-current source.

The two latch relays 177 and 213, are, therefore, energized and are latched in their energized positions by latches 227 and 229 adapted 80 to be tripped by electromagnetic tripping devices 231 and 233, the exciting circuits of which will be discussed hereinafter.

By reason of the excitation of the relay 177, 85 a circuit is closed from one alternating-current bus line 59, through conductor 235, a movable contactor 237 of the latch relay 177, conductor 239, the main windings 241 of the motor 243 that drives the program controller 245 and conductor 247, to the remaining bus line 73 of the 90 alternating-current source.

The motor 243 that drives the program controller 245 is of the induction type and its direction of rotation is predetermined by the orientation of the terminals 249 and 251 of its main 95 winding 241 relative to the terminals 253 and 255 of its starting or "teaser" winding 257. The relative electrical orientation of the "teaser" winding 257 and the main winding 241 is predetermined by the particular relay of the inter- 100 locked pair 132 that is in an energized condition.

As has been assumed hereinabove, the relay 133 is energized and, because it is energized, the remaining relay 131 of the pair 132 is deenergized in spite of the fact that both time-delay relays 105 93 and 141, associated with the pair 132, are now energized. Consequently, a circuit is closed through the "teaser" winding 257 that extends from one terminal 59 of the alternating-current source, through conductor 235, the contactor 237 110 of the latch relay 177, conductors 239, 259 and 260, a movable contactor 261 of the excited relay 133 of the interlocked pair 132, conductors 263 and 265, a movable contactor 267 of a reversing relay 269, the function of which will be discussed 115 hereinafter, conductor 271, the "teaser" winding 257, conductors 273 and 274, the remaining movable contactor 275 of the reversing relay 269, conductors 277 and 279, a second contactor 281 of the excited relay 133 of the interlocked pair 132 120 and conductors 283 and 285, to the remaining bus line 73 of the alternating-current source. It is to be noted that the condition of the interlocked pair of relays has now predetermined the direction of rotation of the motor 243 if the condition of the reversing relay 269 is disregarded, and we shall, for the present, disregard it. If the remaining relay 131 of the pair 132 had been energized, the direction of rotation of the motor 243 would have been of opposite polarity to its 130 present direction. The corresponding "teaser" coil circuit for the relay 131 extends from a bus line 59 of the alternating-current source, through conductor 235, the contactor 237 of the relay 177, conductors 239, 259 and 260, a contactor 287 of 135 the energized relay 131 of the pair 132, conductors 279 and 277, the movable contactor 275 of the reversing relay 269, conductors 274 and 273, the "teaser" coil 257 of the motor 243, conductor 271, the remaining movable contactor 267 of the 140 reversing relay 269, conductor 265, a second contactor 289 of the energized relay 131 of the pair 132 and conductors 283 and 285, to the remaining bus line 73 of the alternating-current source.

It will be noted that, while the terminals 249 145 and 251 of the main winding 241 were connected, respectively, to the terminals 255 and 253 of the "teaser" winding 257 in the first hypothetical case, the terminals 249 and 251 of the main winding 241 are connected, respectively, to the ter- 150

minals 253 and 255 of the "teaser" winding, in the latter hypothetical case. Hence, if the conditions of the reversing relay 289 remain unchanged, the motor 243, in the one case, rotates in a direction 5 opposite to its direction of rotation in the second case.

It will be noted that the latch relay 177, energized from the contactor 181 of the time-delay relay 165, is equipped with a plurality of contactors 175 and 291 through which the circuits through the coils 191, 203, 293, and 295 of the relays 193, 79, 67 and 297, associated with the signal lamps 1, are opened when the relay 177 becomes energized.

15 The exciting coil of the relay associated with the "go" lights 5 along one highway 13, was included in a circuit extending from one direct-current bus line 83, through conductors 171 and 173, the contactor 175 of the latch relay 177, conductors 183 and 185, the movable contactor 187 of the excited relay 115 of the interlocked pair 117, conductor 189, the exciting coil 191 of the relay 193 and conductor 195, to the remaining bus line 97 of the direct-current supply source. The 20 circuit is now broken by the excitation of the relay 177 and the disengagement of the contactor 175 from its corresponding fixed contacts 299.

25 The circuit through the exciting coil 203 of the relay 79, associated with the stop lights 3 on the same highway 13, was originally opened by the excitation of the relay 115 of the interlocked pair 117 and now remains in open position, even if the circuit through the coil 121 of the relay 115 is opened, since the movable contactor 175 of the 30 latch relay 177 is in the circuit and is latched in open position.

35 The exciting coil 293 of the relay 67, associated with the "stop" signals 7 on the remaining highway 15, was in a circuit extending from one direct-current bus line 83, through the lead 171, the contacts 291 of the latched relay 177, conductors 301 and 303, a movable contactor 305 of the unexcited relay 113 of an interlocked pair 117, conductor 307, the exciting coil 293 of the 40 relay 67 and conductor 195, to the remaining bus line 97 of the direct-current supply source. The circuit is now broken by the disengagement of the contactor 291 from its fixed contacts 309.

45 The exciting coil 295 of the relay 297, associated with the "go" signal 9 of the highway 15, is in open position by reason of the fact that its circuit is broken between the fixed contactors 311 of the unexcited relay 113 of the pair of interlocked relays 117. The circuit also contains 50 the fixed contacts 309 of the latch relay 177 which are not engaged by the corresponding movable contactor 291 by reason of the fact that the relay 177 is energized and latched in the energized condition.

55 On the other hand, it should be noted that the relays 193, 79, 67 and 297 are successively energized through the brushes 313 or 315 and 317 of the program controller 245. However, before this condition is attained, the brushes 313 or 315 must engage the conducting segment 319 of the controller 245 and, consequently, the "caution" signals 11 are displayed. The circuit of the "caution" signals 11 extends from one alternating-current bus line 59, through conducting 60 321, the movable contactor 323 of the relay 297, associated with the "go" signals 9 along one highway 15, conductor 325, the movable contactor 327 of the relay 67, associated with the "stop" signals 7 along the same highway, conductor 329, 65 the movable contactor 331 of the relay 193, as-

sociated with the "go" signals 5 along the remaining highway 13, conductor 333, the movable contactor 335 of the relay 79, associated with the "stop" signal 3 along the remaining highway 13, conductor 337, the "caution" signals 11 connected in parallel relationship and conductor 71, to the remaining bus line 73 of the alternating-current source.

70 The motor 243 is now rotating in a direction predetermined by the condition of the relay system and this direction is of such polarity that the lane 13 along which the original "go" signal 5 was displayed retains this signal after the caution signal 11 is displayed. With reference to the drawings, the program controller 245 is now rotating in a counter-clockwise direction. Consequently, the circuits through the exciting coils 191 and 293 of the relays 193 and 67, associated with the "go" signals 5 along one highway 13, and the "stop" signals 7, along the remaining highway 15, are energized.

75 The circuits through the coil 191 of the relay 193, associated with the "go" signal 5, is as follows: from one direct-current bus line 83 through conductors 171 and 339, a movable contactor 341 of the second latch relay 213, excited from the time-delay relay 165, conductor 343, the brush 317 adapted to engage a collar 345 on the shaft 347 of the program-control motor 243, the conducting segment 319 of the program controller 245, the brush 313, now in engagement with the conducting segment 319, conductors 349, 307 and 351, a second contactor 353 of the latch relay 213, conductors 355 and 189, the exciting coil 191 of the relay 193, associated with the "go" signal 5, and conductor 195, to the remaining bus line 97 of the direct-current source.

80 The exciting coil 293 of the relay 67, associated with the "stop" signal on the highway 15, is also energized through the program controller 245, the circuit being as follows: from one direct-current bus line 83, through conductors 171 and 339, the movable contactor 341 of the relay 213, conductor 343, the brush 317 of the program controller 245, the collar 345 on the shaft 347 of the program-control motor 243, the conducting segment 319 of the program controller 245, the brush 313 in engagement therewith, conductors 349 and 307, the exciting coil 293 of the 85 relay 67 and conductor 195, to the remaining bus line 97 of the direct-current source.

85 As long as the brush 313 continues in engagement with the conducting segment 319 of the program controller 245, the two relays 193 and 67, associated with the signals 1 at the intersection 12, are energized. The circuits through the contactors of these relays have been traced hereinabove and it is noted that a "go" signal 5 is indicated for the highway 13, while the "stop" signal is displayed along the remaining highway 15.

90 When the program controller 245 rotates to such point that the first brush 313 is disengaged from the conducting segment 319, the relays 193 and 67 are again deenergized, and the "caution" signal 11 is displayed along both highways. At the same time, a circuit is completed from one direct-current bus line 83, through conductors 215 and 357, the exciting coil 359 of one trip relay 233, conductors 361 and 363, the contactors 365, 367, 369 and 371 of the relays 193, 79, 67 and 297, associated with the signalling system 1, to the remaining bus line 97 of the direct-current source. A second and similar circuit is also com- 95

pleted through the coil 373 of the relay 231, associated with the latch 227 of the relay 177, the coil 373 of the latter relay 231 being in parallel with the coil 359 of the former trip relay 233.

5 The latches 227 and 229 are, therefore, removed, and the cores 375 and 377 of the latch relays 177 and 213 are free to drop if the circuits through their coils 179 and 211 are open. However, it is to be noted that the circuits 10 through the coils 179 and 211 are broken only through the contactor 181 of the time-delay relay 165. The relay 165 is of such structure that its core 379 is not raised for a period sufficient to give the segment 319 on the program controller 245 sufficient time to move into engagement with the remaining brush 315. The exciting coils 295 and 203 of the relays 297 and 79, associated with the "stop" signals 3 and the "go" signals 9 on the highways 13 and 15, respectively, are, therefore, energized, and the "go" signal 9 is displayed along the highway 15, while the "stop" signal 3 is displayed along the highway 13. The circuits through the coils 295 and 203 of the relays 297 and 79 are similar to 25 the circuits through the coils 191 and 293 of the other two relays 193 and 67 and, therefore, need hardly be traced herein.

When the program controller 245 rotates to the position wherein the brushes 313 and 315 are again not in engagement with the conducting segment 319, the trip coils 359 and 373 are again energized and, unless the time-delay relay 165 has been reenergized by the presence of a vehicle along both highways 13 and 15, the latch relays 35 177 and 213, being deenergized, their cores 375 and 377 and the system revert to their original conditions.

It is to be noted that the conducting segment 319 of the program controller 245 may stop in 40 either of two positions relative to the brushes 313 and 315. That is to say, it may stop in the position indicated in the drawings or it may stop in a position 180° therefrom. The position in which the conducting segment 319 of the program controller 245 stops is determined by the condition of the intersection when the latch relays 177 and 213 are tripped.

It is seen that the direction of rotation of the motor 243 is dependent on the position in which 50 the conducting segment 319 of the program controller 245 is oriented when the program controller stops. For this reason, the reversing relay 269 is provided, and its movable contactors 267 and 275 are so adjusted that the direction of 55 rotation of the motor 243 is polarized in accordance with the latest position of the program-control conducting sector 319.

The circuit through the coil of the reversing relay extends from one direct-current bus line 60 97, through conductor 379, the coil 381 of the reversing relay 269, conductor 283, one brush 285 associated with a disc 287 supported on the shaft 347 of program-control motor 243, a conducting segment 389 on the disc 287, if the conducting 65 segment 319 of the program controller 245 is

oriented in such direction as to require the excitation of the reversing relay 269, a collar 391 coaxial with the shaft 347 of the program-control motor 243, a brush 393 engaging the collar 391 and conductor 395, to the remaining direct-current bus line 83.

It will be noted that, for the condition illustrated in the drawings, the reversing relay 269 is deenergized. However, if the program controller stops in a position 180° from the position shown, the reversing relay 269 is energized, and the direction of rotation of the motor, as predetermined by the interlocked relays 131 and 133, is reversed by the reversing relay 269.

In the described embodiment, my invention has been illustrated as applied to a specific system of relays. It is to be noted that my invention may be practiced with a system unlike that herein set forth. In the present embodiment of my invention, eighteen relays are incorporated. It will be 90 recognized that many combinations may be attained with a larger number of relays and that, consequently, my invention should not be restricted to the specific circuits shown herein.

Finally, it should be noted that the representation of the time-delay relays 93, 141 and 165, as dash-pot relays, is to be regarded only as symbolical as time-delay relays are well known in the art and a relay of any well known type may be utilized.

Although I have shown and described certain specific embodiments of my invention, I am fully aware that many modifications thereof are possible. My invention, therefore, is not to be restricted except insofar as is necessitated by the prior art and by the spirit of the appended claim.

I claim as my invention:

A traffic control system for a plurality of highways comprising traffic signalling means provided with stop, caution and go signals for each of said highways, means cooperating with said signalling means to normally energize said stop signal for all of said highways, means to be vehicle actuated disposed on each of said highway, means to respond to the vehicle responsive means on one of the highways when it is actuated by a vehicle moving along said highway to deenergize the stop signal and to energize the go signal for the said highway, means responsive to the vehicle responsive means on another highway when it is actuated within a predetermined time of the actuation of said first named vehicle responsive device to deenergize said stop signal and to energize the go signal for said last named highway, at least a predetermined period of time after said go signal for said first mentioned highway has been energized, and to simultaneously reenergize the stop signal on said first named highway and means for energizing said caution signals for all of said highways for a predetermined interval of time between the transfer of a go signal from said first named highway to said last named highway and a stop signal from said last named highway to said first named highway.
